UNITED STATES PATENT OFFICE.

EDWARD CLIFF, OF NEWARK, NEW JERSEY, ASSIGNOR TO CLIFF AND
GUIBERT COMPANY, OF NEW YORK, N. Y., A CORPORATION OF NEW
YORK.

DESIGN FOR A HOSE-RACK FRAME.

SPECIFICATION forming part of Design No. 35,452, dated December 17, 1901.

Application filed November 14, 1901. Serial No. 82,321. Term of patent 7 years.

To all whom it may concern:

Be it known that I, EDWARD CLIFF, a citizen of the United States, residing at Newark, in the county of Essex and State of New Jersey, have invented and produced a new and original Design for a Hose-Rack Frame, of which the following is a specification, reference being had to the accompanying drawings, forming a part thereof, and in which—

Figure 1 is a side elevation of a hose-rack frame bearing and incorporating my design, and Fig. 2 is an end view of same.

The leading feature of my design consists in the form and configuration of the hose-rack frame, substantially as shown in the drawings.

In the drawings, A designates the side of the hose-rack frame, and B the hub thereof,

said hub being of cylindrical or rounded outline and horizontally disposed, while the side frame A is semicircular in outline and comprises the edge rim or flange C and spokes D, the latter radiating from the hub portion B, and the structure as a whole presenting an original and attractive appearance and configuration, as shown.

What I claim is—

The design for a hose-rack frame, substantially as shown and described.

Signed at New York, in the county and State of New York, this 13th day of November, 1901.

EDWARD CLIFF.
